UNITED STATES PATENT OFFICE.

JAMES N. HEALD AND ALDEN M. DRAKE, OF WORCESTER, MASSACHUSETTS, ASSIGNEES
TO HEALD MACHINE COMPANY, OF WORCESTER, MASSACHUSETTS, A CORPORATION
OF MASSACHUSETTS.

INTERNAL-GRINDING MACHINE.

Application filed April 11, 1921. Serial No. 460,211.

To all whom it may concern:

Be it known that we, JAMES N. HEALD and ALDEN M. DRAKE, citizens of the United States, both residing at Worcester, in the county of Worcester and State of Massachusetts, have invented a new and useful Internal-Grinding Machine, of which the following is a specification.

This invention relates to a machine for producing ground surfaces on metal and particularly to a machine for grinding internal surfaces. In such machines it is customary to support the work on a work spindle rotatable in fixed bearings and to mount the grinding wheel spindle on a carriage movable axially relative to the work. During the grinding operation a slow automatic axial wheel feed is desired, while rapid manual operation is preferred for withdrawing the tool to permit gauging or removal of the work.

It is the general object of our invention to provide improved means for controlling two different feeding mechanisms, so devised that a quick change may be made from one feed to the other and that only one feeding mechanism may be connected to move the carriage at any one time.

In the preferred form, this desired end is accomplished by the use of a single operating lever which may be moved to render either one of two clutch connections operative and the other inoperative.

A further feature of our invention relates to the provision of a control device by which the feed may be changed from automatic to manual, at the same time disconnecting the driving power from the work spindle and preferably applying a brake thereto so that rotation of the work will be stopped promptly during the withdrawal of the grinding wheel. This permits the operator to immediately gauge the work or remove a finished piece of work without loss of time.

Our invention further relates to arrangements and combinations of parts which will be hereinafter described and more particularly pointed out in the appended claims.

A preferred form of our invention is shown in the drawings in which—

Fig. 1 is a front elevation of our improved machine;

Figs. 2, 3 and 4 are enlarged fragmentary details to be described;

Fig. 5 is a front elevation of the automatic feed reversing mechanism;

Fig. 6 is a sectional side elevation thereof taken along the line 6—6 in Fig. 5;

Fig. 7 is a sectional elevation of the vertical feed shaft for the wheel carriage;

Fig. 8 is a plan view of the feed shift lever;

Fig. 9 is a detail view looking in the direction of the arrow 9 in Fig. 8, and

Fig. 10 is a plan view of one of the clutches shown in Fig. 7.

Referring to the drawings, we have shown a grinding machine comprising a base 20 on which a work spindle 21 is rotatable in bearings 22. The spindle is provided with a driving pulley 23 connected by a belt 24 to a cone pulley 25 which, in turn, is connected by a second belt 26 to a cone pulley 27 loose on a driving shaft 28. The shaft 28 may be driven in any convenient manner as by a belt 29 and pulley 30. A clutch 31 is provided for the cone pulley 27 and is controlled by a sliding sleeve 32 positioned by a depending arm 33 of a three-armed lever 34.

The lever 34 is pivoted at 35 on the frame 20 and a second arm 36 thereof is provided with a brake 37 adapted to engage one of the surfaces of the cone pulley 27. The third or upwardly extending arm 38 of the lever 34 has a pin and slot connection with an arm 39 fixed to a cross shaft 40. A lever 41 is fixed to the outer end of the cross shaft and comprises an upwardly extending handle 42 and a laterally extending slotted arm 43.

When the lever 42 is moved to the left in Fig. 1, the brake 37 is released and the sleeve 32 is pushed in to tighten the clutch 31 and connect the cone pulley to the driving shaft 28. At the same time a pump (not shown) is brought into operation to force water or other liquid through the pipe 44 to the work mounted on the spindle 21. A spring

plunger 45 (Fig. 4) holds the clutch sleeve 32 normally in its withdrawn position but permits the same to be yieldingly moved to operative position when desired.

5 The work may be secured to the spindle 21 in any desired or convenient manner and is preferably covered during the grinding operation by a casing or guard 46.

The grinding wheel W is mounted on the 10 end of a spindle 50, rotatable in a wheel head 51 and driven in any convenient manner as by belts 52 and 53. The head 51 is mounted for transverse adjustment on a wheel table or carriage 54, mounted to slide on the base 15 20 and preferably provided with a rack (not shown) engaged by a pinion 55 (Fig. 7) fixed to the upper end of a vertical feed shaft.

Two separate mechanisms are provided 20 for rotating the shaft 58. One of these comprises a hand wheel 59 (Fig. 1) mounted at the front of the grinding machine on a short shaft 60, the rear end of which is connected by spiral gears 61 and 62 (Fig. 7) to a clutch 25 casing 63 loosely rotatable on the shaft 58. An expansible clutch member 64 (Fig. 10) is formed integral at one point in its circumference with a clutch hub 65 fixed to the shaft 58. A lever 66 on the hub 65 is positioned for engagement by one beveled end of a double sliding sleeve 67 (Fig. 7) which is positioned by the yoke shaped arm 68 (Fig. 8) of a clutch lever 69. The lever 69 is mounted on a fixed pivot and has a handle 30 portion 70 in which is mounted a stud or pin 71 adapted to extend into a slot 57 (Fig. 9) in the end of the arm 43 of the handle lever 41 previously described. The stud 71 may be positioned as shown in Fig. 8 to connect the 35 two levers, or may be withdrawn to disconnect the levers, and will be held yieldingly in either position by a spring plunger 72.

The power mechanism for rotating the shaft 58 comprises a driving shaft 73 (Fig. 45) continuously rotated by a belt 74 which connects a cone pulley 75 on the shaft 73 to a small cone pulley 76 (Fig. 1) on the right hand end of the driving shaft 28. The shaft 73 is thus continuously rotated at either one 50 of two desired speeds. A double clutch member 77 is keyed to the shaft 73 and is slideable to engage clutch faces on either one of two bevel pinions 78 and 79 meshing with a bevel gear 80 fixed to the front end of a 55 short shaft 81 (Fig. 6). A worm 82 on the shaft 81 engages a worm wheel 83 (Fig. 7) which is fixed to a second clutch casing 84 loosely rotatable on the shaft 58 but adapted to be connected thereto by an expansible 60 clutch member 85 as in the device previously described. The member 85 is controlled by a clutch lever 86 mounted for engagement by the beveled lower end of the sliding sleeve 67.

65 The reversing clutch member 77 (Fig. 5) is

positioned by a reverse lever 90 mounted on a fixed stud 91 and having a pin 92 positioned for engagement by dogs 93 (Fig. 1) longitudinally adjustable on the table or carriage 54. Only one of these dogs is 70 shown in the drawings but it will be understood that a pair of dogs is commonly provided to reverse the clutch at each end of the desired travel of the carriage.

Spring levers 89 and locking cam plates 75 (not shown) are provided for shifting the reverse lever and clutch quickly from one operative position to the other. The details and operation of this mechanism need not be further described as it forms no part 80 of the present invention.

A third dog 94 (Fig. 1) on the table 54 is positioned to engage the upper end of the lever or handle 42 when the table and grinding wheel are fully withdrawn from the 85 work.

Having described the construction of our improved grinding machine, we will now describe its operation. When the handle 42 is moved to the left in Fig. 1, or the handle 90 70 is pulled upward, the brake is released and the work is rotated as previously described. At the same time the yoke arms 68 (Fig. 8) are moved downward, causing the clutch sleeve 67 to engage the lower, clutch casing 84 with the shaft 58. The machine is thus connected for automatic feed and reversal of the wheel carriage 54 under the control of the dogs 93.

When it is desired to withdraw the wheel 100 and stop the work for examination or removal, the handle 42 may be pulled to the right, thus shifting the clutch sleeve 67 to connect the upper clutch casing 63 to the clutch 64 and shaft 58, and at the same time 105 to disconnect the work spindle and apply the brake to the cone pulley 27, also stopping the operation of the pump. The hand wheel 59 is immediately available for withdrawing the wheel carriage 54, although it 110 is fully disconnected and stands idle during the automatic feed of the carriage. If it is desired to shift the feed and withdraw the carriage 54 without stopping the work 115 spindle, the stud 71 may be pulled outward to disconnect the arm 43 from the handle 70. When the carriage is moved to the extreme right, the dog 94 will move the handle 42 to stop the work.

The advantages of our improved construction are thus readily apparent and it will be evident that changes and modifications can be made in our invention by those skilled in the art, without departing from the spirit and scope thereof as set forth in the claims. 125 Therefore, we do not wish to be otherwise limited to the details herein disclosed but what we claim is:—

1. In a grinding machine, a wheel spindle, driving means therefor, a grinding wheel, 130

- a wheel table, power feeding means therefor, manual feeding means therefor, and controlling mechanism effective to disconnect said spindle driving means and to simultaneously render said power feeding means inoperative and said manual means operative.
2. In a grinding machine, a work spindle, driving means therefor, a controlling device for said driving means, a grinding wheel, a wheel table, means to feed the wheel table manually, additional means to feed said table by power, a second controlling device by which said manual and power feeding means may be rendered separately operable, and a connection between said devices whereby they may be simultaneously actuated to disconnect said driving means and to connect said table feeding means for manual operation.
3. In a grinding wheel, a work spindle, driving means therefor, a clutch lever controlling said driving means, a driving wheel,
- a wheel table, means to feed the wheel table manually, additional means to feed said table by power, a second clutch lever by which said feeding means may be rendered separately operable, and a detachable connection between said clutch levers whereby they may be simultaneously actuated to disconnect said spindle driving means and to connect said table feeding means for manual operation.
4. In a grinding machine, a work spindle, a clutch lever controlling the work spindle, a grinding wheel, a wheel table, means to feed the wheel table, a second clutch lever controlling the table feed, and a detachable connection between said clutch levers providing for movement of said levers separately or simultaneously.

In testimony whereof we have hereunto affixed our signatures.

JAMES N. HEALD.
ALDEN M. DRAKE.
